Ralph La Rue Du Bois, 4242 E. 111th St.,
Tulsa, Okla. 74135

Filed Mar. 15, 1968, Ser. No. 10,990

Term of patent 14 years

U.S. Cl. D80—8

Int. Cl. D6—07

FIG. 1

FIG. 3

FIG. 1 is an elevational view taken from one side of a garment hanger showing my new design, a portion of one end being broken away for convenience of illustration, the opposite side being a mirror image of the side shown;

FIG. 2 is a top plan view thereof; and

FIG. 3 is an end elevational view thereof.

The bottom side of the coat, garment, or clothes hanger forms no part of the design of this invention.

I claim:

The ornamental design for a garment hanger, substantially as shown and described.
